UNITED STATES PATENT OFFICE.

FRED L. MILLS, OF OAK PARK, ILLINOIS, ASSIGNOR TO MILLS NOVELTY COMPANY, OF CHICAGO, ILLINOIS, A CORPORATION OF ILLINOIS.

DESIGN FOR A VENDING-MACHINE CABINET.

Application filed March 1, 1924. Serial No. 8,797. Term of patent 14 years.

To all whom it may concern:

Be it known that I, FRED L. MILLS, a citizen of the United States, residing at Oak Park, county of Cook, and State of Illinois, have invented a new, original, and ornamental Design for a Vending-Machine Cabinet, of which the following is a specification, reference being had to the accompanying drawing, forming a part hereof. The figure shows a perspective view of a vending machine cabinet, embodying my new design.

I claim:

The ornamental design for a vending machine cabinet, as shown.

FRED L. MILLS.
